BIRD HOUSE

William G. Bley, Richboro, Pa., assignor of one-half to Richard C. Spurgeon, Lansdale, Pa.

Filed Mar. 11, 1960, Ser. No. 59,704

Term of patent 14 years

(Cl. D31—2)

FIG. 1.

FIG. 2.

FIG. 3.

FIG. 4

FIG. 5

Fig. 1 is a front elevational view of a bird house, showing my new design;

Fig. 2 is a left side elevational view thereof;

Fig. 3 is a right side elevational view thereof;

Fig. 4 is a rear elevational view thereof; and

Fig. 5 is a bottom view thereof, but with the floral area omitted for convenience of illustration.

I claim:

The ornamental design for a bird house, as shown.
